UNITED STATES PATENT OFFICE

106,310

DESIGN FOR BINOCULARS

Renato Ludovici, Chicago, Ill., assignor to Ella G. Brandstetter, Chicago, Ill., doing business as Alto Mfg. Company

Application August 18, 1937, Serial No. 71,155

Term of patent 7 years

To all whom it may concern:

Be it known that I, Renato Ludovici, a subject of the King of Italy, residing in Chicago, in the county of Cook and State of Illinois, have invented a new, original, and ornamental Design for Binoculars, of which the following is the specification, reference being had to the accompanying drawing, forming part thereof.

In the drawing:

Fig. 1 is a perspective view of binoculars showing my design in open position.

Fig. 2 is a perspective view of binoculars showing my design in closed position.

I claim:

The ornamental design for binoculars substantially as shown.

RENATO LUDOVICI.
